G. H. WHEARY.
CLOTHES RETAINER.
APPLICATION FILED JULY 14, 1915.

Patented Oct. 23, 1917.

ATTORNEYS.

UNITED STATES PATENT OFFICE.

GEORGE HENRY WHEARY, OF RACINE, WISCONSIN.

CLOTHES-RETAINER.

1,243,785.

Specification of Letters Patent. Patented Oct. 23, 1917.

Application filed July 14, 1915. Serial No. 39,786.

To all whom it may concern:

Be it known that I, GEORGE HENRY WHEARY, a citizen of the United States, and resident of Racine, in the county of Racine 5 and State of Wisconsin, have invented new and useful Improvements in Clothes-Retainers, of which the following is a description, reference being had to the accompanying drawings, which are a part of this specification.

My invention has relation to improvements in clothes retainers, particularly adapted, although not solely, for use in wardrobe and other trunks.

Trunks, especially of the wardrobe type, are usually provided with flat clothes retainers or followers, of rectangular form, which are adapted to hold garments suspended from hangers connected to the upper portion of the wardrobe section of the trunk, tightly in position to prevent the disarrangement of the garments during transportation of the trunk.

The primary object of my invention is to provide an improved form of garment retainer, which is not only simple in construction and also capable of being quickly adjusted in position or removed, but which also is capable of being operated to change 30 the adjustment thereof in a most convenient and simple manner.

With the above primary, and other incidental, objects in view, the invention consists of the devices and parts, or the equivalents thereof, as hereinafter more fully set forth.

In the accompanying drawing,

Figure 1 is a front view of a fragment of the wardrobe section of a wardrobe trunk, 40 showing in dotted lines the other section of the trunk as swung to an open position;

Fig. 2 is a horizontal section on the line 2-2 of Fig. 1, looking downwardly in the direction of the arrows;

Fig. 3 is a cross section on the line 3-3 of Fig. 1, looking in the direction of the arrows, and showing clearly one of the supporting rails for the retainer bar; and

Fig. 4 is a vertical section on the line 50 4-4 of Fig. 1 looking in the direction of the arrows.

Referring to the drawing, the numeral 5 indicates the wardrobe section of a trunk, and 6 the other section thereof. The wardrobe section is of ordinary construction, and

is adapted to be provided in the upper portion thereof with the usual garment hangers (not shown) which support the garments in full length position.

Secured to opposite sides of the wardrobe 60 section, opposite to each other, and at medial points of said sides, are supporting rails 7-7. These rails, at opposite ends are angled so as to provide feet 8-8, which feet are secured to the sides by means of rivets, 65 nails or the like. The major portion of each rail between the terminal feet outstands from the walls or sides of the trunk, as clearly shown in the drawing.

Each rail from its top edge downwardly 70 is provided with a plurality of slots. The upper portion of each slot is straight and narrow, as indicated by the numeral 9, and the lower portion of each slot is enlarged, and preferably of circular form, as indicated by the numeral 10.

The retainer bar 11 is of flat rectangular shape, and is of sufficient length to extend from one side of the trunk to the other.

Secured to the retainer bar, near opposite 80 ends thereof, are straps 12-12, which straps medially are curved outwardly to form circular bearings 13-13 for a round rod 14, said rod being provided intermediate of its ends with the bent-out portion forming a 85 handle 15, which handle normally extends downwardly, as shown in the drawing.

It is desirable, when the handle is grasped and lifted, that some means be provided for limiting such uplift, or in other words, 90 limiting the turning of the rod 14 in an upward direction. To this end, I form the bearings 13-13 with elongated slots 16-16, and through these slots project stop pins 17-17 extending from the rod 14. It is 95 obvious that when the handle 15 is grasped and turned upwardly, the extent of this upward turning will be limited by contact of the pins 17 with the upper ends of the slots 16.

The ends of the rod 14 act in conjunction with the rails 7-7 in supporting the retainer bar in adjusted position. The said ends of the rod 14 on one side are provided with flat faces 18-18, said flat faces being 105 uppermost when the rod is in proper engagement with the rails 7, as clearly shown in Figs. 1 and 2 of the drawing.

In the use of the invention, the garments are suspended in the wardrobe section in 110

the usual way. The retainer bar is then adjusted against the clothing, and in order that the bar may be brought into engagement with the rails 7, the handle 15 is turned upwardly, and this will have the effect of bringing the flat faces at the ends of the rod 14 which are normally in a horizontal plane, to a vertical plane. When these flat faces are thus disposed in a vertical plane, it is evident that the ends of the rod can be readily pushed downwardly into the narrow portions 9 of the slots until they seat themselves in the lower enlarged rounded portions 10 of said slots. The handle 15 is then turned downwardly and this will have the effect of turning the rod 14 so that the flat faces 18 at the ends of said rod will be in a horizontal plane intersecting the lower ends of the narrow portions 9 of the slots, with the result that the ends of the rod cannot be removed from engagement with the slots until the handle is again turned upwardly so as to bring the flat faces 18 in a vertical plane.

25 After the retainer bar is adjusted in the manner above described, if it is found necessary to adjust the retainer bar inwardly to secure greater compression against the suspended clothing, or adjust the same outwardly to diminish the compression, all that is necessary to be done is to turn the handle upwardly, and then pull the ends of the rod out of engagement with the two slots with which they are engaged, and then adjust these ends to two other slots either located farther inward or outward, in accordance with whether the adjustment is to be inwardly or outwardly. The ends of the rod are then made to engage these other slots 40 in the manner fully described with relation to the first referred to slots.

From the foregoing description it will be seen that the clothes retainer is very simple in construction, and is most easily and quickly adjusted both initially and at any time, when necessity requires a change of adjustment.

While the device has been described as particularly adapted for wardrobe trunks, 50 yet I do not wish to be understood as limiting myself to that particular style, inasmuch as the adaptation of the retainer bar and allied parts to other forms of trunks, is considered to be within the spirit and scope of my invention.

What I claim as my invention is:

1. The combination with a pair of spaced rails having a plurality of spaced slots in their upper edge portions, of a bar therefor, 60 said slots being larger below the upper edges of the rails, and a rod turnably connected to said bar, each end of said turnable rod being narrower in one direction than in the opposite direction, said rod ends entering the slots of the rails when the rod is turned

in a certain direction and being locked to the rails when turned in another direction.

2. The combination with a pair of spaced rails having a plurality of spaced slots in their upper edge portions, of a bar therefor, 70 said slots being larger below the upper edges of the rails, outstanding bearings secured to said bar, and a rod turnably mounted in the bearings and having its outer end portions narrower in one direction than in the opposite direction to permit said ends entering the slots when the rod is turned in one position and being locked thereto when turned in another direction.

3. The combination with a pair of spaced 80 slotted rails, of a bar therefor, an outstanding bearing secured to the bar, said bearing provided with an elongated slot, and a rod turnable in said bearing, and provided with a pin projecting into the slot of the bearing, 85 each end of said turnable rod being narrower in one direction than in the opposite direction to permit said ends entering the slots when the rod is turned in a certain direction and being locked to the rails when 90 turned in another direction.

4. The combination with a pair of spaced slotted rails, of a bar therefor, a rod turnably connected to said bar, the said rod provided between its ends with a projecting 95 handle, and each end of said turnable rod being narrower in one direction than in the opposite direction to permit said ends entering the slots when the rod is turned in a certain direction and being locked to the 100 rails when turned in another direction.

5. The combination with a pair of spaced slotted rails, of a bar therefor, a rod turnably connected to said bar, said rod provided intermediate of its ends with a projecting 105 handle, and each end of said turnable rod being narrower in one direction than in the opposite direction, the narrower portion of the bar being uppermost when the handle is turned from its normal position to permit 110 said ends entering the slots of the rails.

6. The combination of a casing, outstanding slotted rails secured to opposite sides of said casing, said rails constructed to be engaged at their slotted portions, a retainer bar, and a rod turnably connected to said retainer bar, and each end of said turnable rod constructed to permit of the entrance of the ends of the rod into some of the slots of the rails, when the rod is turned in one direction, and to permit of the disengagement of said ends from the slots when the rod is turned in the opposite direction.

7. The combination of a casing, rails secured to opposite sides of said casing, said rails provided at a plurality of points along their edges with slots, the outer portions of said slots being narrower than the inner portions thereof, a retainer bar, and a rod turnably connected to the retainer bar, each 120

end of said turnable rod being narrower in one direction than in the opposite direction to permit said rod ends to enter said slots.

8. The combination of a casing, rails secured to opposite sides of the casing, and said rails provided upon their edges with a plurality of slots, the inner ends of said slots being wider than the outer ends thereof, and a rod, each end of said rod being narrower in one direction than in the opposite direction to permit said rod ends to enter said slots.

9. The combination of a casing, rails secured to opposite sides of the casing, said rails provided upon their edges with a plurality of slots, the inner ends of said slots being wider than the outer ends thereof, and a rod, each end of said rod being narrower in one direction than in the opposite direction, and said rod provided intermediate of its ends with a projecting handle, the wider portions of the ends of the rod being in a horizontal plane, when the handle is in its normal position and the narrow portions of said ends of the rod being in line with the

narrow portions of the slots, when the handle is turned from its normal position.

10. The combination of a casing, rails secured to opposite sides of the casing, said rails provided upon their edges with a plurality of slots, the inner ends of said slots being wider than the outer ends thereof, a retainer bar, and a rod turnably connected to the retainer bar, each end of said rod being narrower in one direction than in the opposite direction, and said rod provided intermediate of its ends with a projecting handle, the wider portion of the ends of the rod being in a horizontal plane, when the handle is in its normal position and the narrow portion of said ends of the rod being in line with the narrow portions of the slots, when the handle is turned from its normal position.

11. In testimony whereof, I affix my signature, in presence of two witnesses.

GEORGE HENRY WHEARY.
